UNITED STATES PATENT OFFICE.

STANLEY R. HOWARD, OF EAST MILTON, MASSACHUSETTS, ASSIGNOR TO PNEUMATIC SCALE CORPORATION LIMITED, OF QUINCY, MASSACHUSETTS, A CORPORATION OF MASSACHUSETTS.

BOX-MAKING MACHINE.

Application filed August 20, 1925. Serial No. 51,397.

To all whom it may concern:

Be it known that I, STANLEY R. HOWARD, a citizen of the United States, residing at East Milton, in the county of Norfolk and State of Massachusetts, have invented certain new and useful Improvements in Box-Making Machines; and I do hereby declare the following to be a full, clear, and exact description of the invention, such as will enable others skilled in the art to which it app pertains to make and use the same.

This invention relates to a box making machine and particularly to a machine for making banded pasteboard boxes.

One object of the invention is to provide a box banding machine of novel and improved construction in which provision is made for rendering the banding mechanism inoperative in the event of a jam or abnormal accumulation of boxes at a definite point in the machine.

A still further object of the invention is to provide a box banding machine employing a rotary and reciprocatory box holding member and a die cooperating therewith for receiving and conveying partially banded boxes and in which provision is made for stopping the movement of the box holding member in the event of an accumulation of boxes in the box holding die.

These and other features of the invention will be hereinafter described and particularly pointed out in the claims.

In the drawings the invention is illustrated as embodied in a machine for making pasteboard boxes, wherein Figure 1 is a side elevation with portions in section of a sufficient portion of the machine to enable the invention to be understood; Fig. 2 is an enlarged detail in side elevation of a part of the control mechanism utilized in stopping the machine; Fig. 3 is a rear elevation of a portion of the mechanism shown in Fig. 2; and Fig. 4 is a section on the line 4—4 of Fig. 3.

The box making machine illustrated in the drawings comprises in general, and except as hereinafter pointed out, the construction of machine illustrated in the U. S. Patent to Hogfeldt No. 996,856, of July 4,

1911, and as set forth in said patent the machine comprises, in general a banding or presser roll 10 by which an adhesive banding strip 12 is applied to the periphery of a pasteboard or other box, or to a box cover, 55 positioned upon a rotatable plunger 14. The latter is arranged to be rotated in intermittent cycles, and during each cycle of rotation the banding strip is wrapped completely around the box or cover positioned 60 upon the plunger 14. Thereafter, and before the next cycle of rotation of the plunger 14, provision is made for transferring the box into a reciprocatory die 18, and the remaining operations in folding in the band- 65 strip over the edges of the sides of the box are completed while the box or cover is held by the die 18. As illustrated in Fig. 1, the plunger 14 is mounted upon and secured to the end of a sleeve 30 journaled in suitable bearings 32 in the machine frame and capable of reciprocation longitudinally of the machine frame. Rotation is imparted to the plunger 14 through the sleeve 30 from a driven pulley 34 through a clutch 36 of any 70 usual or preferred construction provided with a movable member 37 having a pin 38 received within the slotted end 39 of a lever 40 connected by a link to the usual shipper lever 44, as shown. When the clutch 36 is 75 thrown in, the rotations of the driven pulley 34 are transmitted to the shaft 51 through the clutch 36 and thence through a pair of cooperating gears 46, 48 to a counter-shaft 49 having upon the one end thereof an intermittent gear 50 meshing with a pinion 52 upon the sleeve 30. With this arrangement the continuous rotations of the driven pulley 34 are transmitted through the gearing described to impart intermittent cyclic rotation to the plunger 14 and consequently to the box mounted thereon. The reciprocatory motion is imparted to the plunger 14 by a cam 56 upon a shaft 58 geared to and driven from the driven pulley 34, and having a 80 cam groove 59 in which a cam roller 60 mounted upon a lever 62 rides. The end of the lever 62 is connected to a block 63 upon the sleeve 30. Provision is also made for holding the box in the die 18 while the plung-

85
90

100

er 14 is being withdrawn therefrom and for this purpose an ejector plate 67 is mounted on the end of an ejector rod 68 and the latter is extended through the plunger 14 and 5 through the sleeve 30 upon which the plunger is mounted. The ejector plate and rod are yieldingly held in a rearward position with relation to the sleeve 30 by a coil spring 69, see Fig. 1.

10 As previously stated, the die 18 is arranged to reciprocate transversely of the machine, viewing Fig. 1, running in suitable guides 65 and being actuated by suitable mechanism such as is shown and described in said Hogfeldt patent. During the operation of the machine, the banding strip is wrapped around the box or cover on the plunger 14, the latter then moves forward and deposits the box in the die 18. The die 18 is then moved transversely of the machine in the manner fully described in said Hogfeldt patent above referred to and after the remaining banding operations have been performed, the banded box is 20 removed from the die 18 and the latter returned into alinement with the plunger 14. In some instances, however, the completely banded box is not removed from the die so that when the die returns to a position 25 in alinement with the plunger 14 and the next box is deposited in the die by the plunger 14 as the latter is moved forward by the cam 56 a condition obtains in which there is an accumulation of boxes in the die 18, such as illustrated in Fig. 1, wherein 30 represents the first box and 72 the succeeding box.

35 The plunger 14 is preferably made yieldingly mounted on the end of the sleeve 30, and as herein shown comprises two parts 71, 73, connected in slidable relation and having springs 75 which are adapted to permit the part 71 to yield when it engages accumulated boxes within the die 18, 40 thus relieving the strain.

45 Because of the fact that it is desirable to reciprocate the plunger 14 during a definite stroke from the cam 56, it is desirable in addition to the yieldable construction 50 of plunger 14 that provision be made for throwing out the clutch 36 controlling both the rotation and the reciprocation of the plunger 14 and its sleeve 30, in the event that accumulation of boxes such as 70, 72 55 takes place within the die. As herein shown, this is accomplished by electrically operated mechanism including a device 80 comprising a casing 82 secured to the end of the shipper lever 44 by a link or rod 85 screwed into one end thereof and fastened by a nut 86. The casing 82 has extended therein a second rod 87 connected to the end of the lever 40 controlling the actuation of the clutch 36, and this rod 60 65 87 is yieldably and slidably mounted with

relation to the casing, a coil spring 90 embracing the rod 87 and operating to hold the casing in the position illustrated in Fig. 1. It will be apparent that the shipper lever 44 is connected with the clutch lever 40 through a yieldable connection comprising the casing 82, the coil spring 90 and the collar 91 secured upon the rod 87. When the clutch is to be set, the shipper lever 44 is thrown to the right in the direction of the arrow, Fig. 1, from the position therein illustrated, operating to draw the casing to the left, Fig. 1, compressing the coil spring 90, or in other words elongating the link connection between the end of the shipper lever 44 and the clutch lever 40. This operates to position a locking member 92 pivoted at one end upon the collar 91, the other end being pivotally connected to the casing by a link in a substantially horizontal position under the end of a pivoted latch 97 in the form of a bell crank, the second end of the latch being pivoted at 98 to the armature 99 of a solenoid 100 of standard construction. The solenoid 100 is connected in series with the battery 102 and in circuit with suitable contact mechanism, as will be described, by which a contact is made when a condition in the operation of the machine corresponding to that represented in Fig. 1 obtains.

60 In order to close the circuit to actuate the solenoid 100 and to permit the spring 90 to throw the clutch lever 40 to stop the machine when the plunger 14 in its forward stroke encounters an accumulation of boxes within the die 18, the rear end of the ejector rod 68 is provided with a contact member 110 adapted to make contact at such time with a contact block 112 mounted upon one end of a lever 114 pivoted upon a stud 115 carried by a bracket 116 secured to the machine frame. The contact block 112 is electrically connected by a spring contact 118, the end of which is upturned slightly and rides upon a stationary contact 119 or terminal member, connected by the lead 120 to one side of a timing contact comprising two spring members 121, 122 provided with contact points 123, 124 arranged to be brought into contact by a positively driven cam 125 engaging a cam roller 126 on the end of an arm 127 having an insulating piece 128 which engages the lower spring 122 to raise it to bring the point 124 into engagement with the point 123 upon the stationary contact, when the high point of cam 125 passes under the cam roller 126 as illustrated in Fig. 3. The cam 125 is so timed as to close the contact at this point when the plunger 114 has reached the end of its forward travel. Ordinarily under the normal operation of parts in which there is only a single thickness of box present in the die 120 125 130

18 the contact blocks 110, 112 will at this time have become separated, the upper contact 110 being at its extreme position to the left, viewing Fig. 4, corresponding to the forward position of the plunger. When, therefore, the timing contacts 123, 124 close the circuit under the influence of the positively timed cam 125, the circuit is still open between the contact blocks 110, 112, so that the solenoid 100 of the clutch actuating mechanism is not actuated or energized. When, however, in its forward movement the ejector plate 67 and the plunger 14 meet an accumulation of boxes, both the plunger and the ejector yield, compressing the springs 75 and 69 and causing the contact blocks 110, 112 to remain in contact in the position illustrated in Fig. 4, so that when the contact is subsequently made between the timing contacts 123, 124 a definite circuit is established through the machine frame, through the solenoid 100, through the timing contacts 123, 124, through the contact blocks 110, 112 to the machine frame, thus energizing the solenoid, releasing the latch 97 and allowing the coil spring 90 to expand, thrusting the link or rod 87 to the left relative to the casing 82, consequently operating to throw out the clutch 36 and stop the machine.

During the normal operation of the machine in which the banded box is removed from the die 18 at near the end of each cycle of operation of the machine, the circuit just described will be opened at the timing contacts 123, 124 before the plunger 14 has reached a point in its rearward movement such that the contact blocks 110, 112 are brought into contact to close the circuit, so that at such time the solenoid 100 is not energized.

During the normal operation of the machine when there is no accumulation of boxes in the die 18, the ejector plate 67 and ejector rod 68 occupy an extreme position to the left, viewing Fig. 1, at the forward stroke of the cam 56, permitting at this time a latch 130 on a bell crank 132 pivoted at 115, to be snapped upwardly by a spring 134 into a position in back of a second block 136 on the rear end of the ejector rod 68. Then, as the plunger is moved rearwardly, the coil spring 69 compresses and the ejector plate 67 is held by the latch 130 operating to hold the box in the die 18. When the rise 138 on the face of the cam 125 engages the roll 139 on the second arm of the bell crank 132, the latch 130 is disengaged, permitting the coil spring 69 to cause the ejector rod 68 and the ejector plate 67 to be rapidly moved rearwardly. When, however, the condition illustrated in Fig. 1 obtains, namely when there is an extra thickness of box in the die 18, the latch 130 is

prevented from snapping in behind the block 136, as will be apparent from an inspection of Fig. 1.

While the preferred form of the invention has been illustrated and described, it is to be understood that the invention may be embodied in other forms within the scope of the following claims.

Having thus described the invention, what is claimed is:

1. In a box making machine, in combination, box banding mechanism including a rotatable and reciprocatory box holding device, a die into which a box is delivered or is introduced by said device upon reciprocation thereof, and means operative when an abnormal accumulation of boxes takes place within the die for preventing reciprocation of said box holding device.

2. In a box making machine, in combination, box banding mechanism, including a rotatable box holder, means for rotating the box holder, a presser for pressing a banding strip against the box or cover held by the box holder, and means operative when an abnormal accumulation of boxes occurs at a definite point in the machine for rendering the box banding mechanism inoperative.

3. In a box making machine, in combination, box banding mechanism including a rotatable and reciprocatory box holding device, a presser cooperating therewith for pressing a banding strip against a box held by said device, a member cooperating with said box holding device to receive the box deposited therein by said device upon its reciprocatory movement, and means for stopping the movement of the box holding device when a plurality of boxes accumulate in said member.

4. In a box making machine, in combination, a movable die, a rotatable and reciprocatory box holding member adapted to deposit a banded box in said die, and means for stopping the rotatable and reciprocatory movement of said box holding member when an accumulation of boxes takes place in said die.

5. In a box making machine, in combination, box banding mechanism including a box holder, a presser member for applying a banding strip to a box held by said box holding device, a die, means for reciprocating the box holding device to deposit a box in said die, and means for controlling the reciprocation and rotary movement of the box holder in accordance with the extent of movement thereof into the said die.

6. In a box making machine, in combination, box banding mechanism including a box holding device, a die into which the box holding device moves to deposit a box in the die, and means for reciprocating the box holding device including a cam, said device having provision for yielding when it en-

gages an abnormal accumulation of boxes within the die.

7. In a box making machine, in combination, box banding mechanism including a box holding device, a die into which the box holding device moves to deposit a box in the die, and means for reciprocating the

box holding device including a cam, said device comprising two parts yieldably connected together.

In testimony whereof I have signed my name to this specification.

STANLEY R. HOWARD.
